Primary Examiner — Susan Bennett Hattan*Assistant Examiner* — Rebecca Tsehay(74) *Attorney, Agent, or Firm* — Hanley, Flight & Zimmerman, LLC(57) **CLAIM**

The ornamental design for a "carrier for use in a diagnostic analyzer," as shown and described.

DESCRIPTION

FIG. 1 is a front right perspective view of a carrier for use in a diagnostic analyzer.

FIG. 2 is a front view of the carrier of FIG. 1.

FIG. 3 is a rear view of the carrier of FIG. 1.

FIG. 4 is a right side view of the carrier of FIG. 1.

FIG. 5 is a left side view of the carrier of FIG. 1.

FIG. 6 is a top view of the carrier of FIG. 1.

FIG. 7 is a bottom view of the carrier of FIG. 1; and, FIG. 8 is a rear right perspective view of the carrier of FIG. 1.

The features shown in broken lines form no part of the claimed design.

1 Claim, 6 Drawing Sheets(56)
